(57) **CLAIM**

The ornamental design for a light fixture, as shown and described.

DESCRIPTION

FIG. 1 is an isometric view of substantially the top of a fixture in accordance with the new design;

FIG. 2 is a top plan view of a light in accordance with the new design;

FIG. 3 is left side elevational view thereof, whereby the opposing side is a mirror image;

FIG. 4 is a front elevational view thereof, whereby the rear is a mirror image thereof;

FIG. 5 is bottom plan view thereof; and,

FIG. 6 is an isometric view of substantially the bottom of a fixture in accordance with the new design.

Whereby broken lines form no part of the claimed invention.
